EYESHIELD FOR HEADGEAR

Humberto Vaca, Detroit, Mich.

Application April 27, 1948, Serial No. 23,429

4 Claims. (Cl. 2—10)

1

This invention relates to head gear such as a cap or the like which is provided with a shield for protecting the wearer's eyes from the direct rays of the sun.

More specifically, the invention is directed to the provision of a shield which is mounted on the underside of the visor of a cap or the like so as to be readily manipulated to either an operative position depending from the visor before the wearer's eyes, or an inoperative position substantially flush with the underside of the visor so as to leave the wearer's view unobstructed. The shield may be considered as in the nature of a shiftable transparent sun shade and is particularly useful to persons whose activities demand that their eyes be protected from the glare of sunlight, such as motorists, baseball players, skiing enthusiasts, and the like.

An object of the invention is to provide a mounting for a shield of this type which is simple from standpoint of manufacture as well as operation. The simple construction results in economy without sacrificing the efficient and positive operation of the shield.

A further object of the invention resides in the provision of a single spring for producing a snap movement of the shield to both the operative and inoperative position, together with the elimination of latches, clips and the like for holding the shield in either of its positions.

Other objects and improvements in the way of construction and operation will become apparent from the following description and drawings, in which

Figure 1 is a view of a cap provided with the shield of this invention, the shield being shown in the operative position.

Figure 2 is a bottom view of a portion of the cap showing the shield in its folded or inoperative position.

Figure 3 is a cross section through the visor of the cap taken substantially along lines 3—3 of Figure 2, illustrating the general arrangement of the shield mounting with the shield in the inoperative position.

Figure 4 is a side view, partly in section, of a portion of the cap showing the shield in the operative position.

Figure 5 is a sectional view on an enlarged scale taken substantially along lines 5—5 in Figure 3 showing a detail of construction of the shield mounting.

Figure 6 is a sectional view on an enlarged scale taken substantially along the lines 6—6 in Figure 3 showing another detail of the shield mounting.

In the drawings I have shown for the purposes of illustration, the shield as applied to the ordinary baseball cap. It will be understood that the shield may be mounted on visors of other

2

types of caps or hats as well, the principle of operation being the same in all cases. As is shown in Figure 1, the cap comprises a body portion 10 which is adapted to fit over the head of the wearer and a visor 11 which is attached to the lower edge of the cap at the front thereof for shading the wearer's eyes. The shield, generally designated at 12, is mounted on the underside of visor 11 and is shiftable from an operative depending position shown in Figure 1 to an elevated inoperative position shown in Figure 3. Shield 12 is preferably formed of a transparent colored material such as plastic or glass which is adapted to serve as a filter for the rays of the sun. The shield may also be formed from a light polarizing material. In order to permit the shield to lie snugly underneath visor 11 in the operative position, it is preferably formed of arcuate cross section which conforms to the shape of the visor. Along its lower edge shield 12 is provided with a notched out portion 13 which provides clearance for the nose of the wearer when the shield is shifted to the operative position as is best shown in Figure 1.

On the underside of visor 11 there is attached as by rivets 14 a support member 15 which extends generally in a forwardly and rearwardly direction at the central portion of the visor. Support member 15 is provided at each side with upturned reinforcing flanges 16 which lend rigidity to the visor. At the rear portion of support 15, flanges 16 are fashioned into channel shaped edges 17 which are turned inwardly towards each other in the form of a guideway on member 15. It will be appreciated that support member 15 may be formed economically from sheet metal by a simple stamping operation. At the front end of support member 15 there is secured as by rivet 14 a leaf spring 18 which extends in a generally rearward direction on member 15. Spring 18 is of shorter length than support 15 and normally tends to flatten out against the bottom face of support 15. At its free end spring 18 is fashioned into a loop 19 through which passes a pin 20. A hinge member 21 is pivoted on pin 20 by means of a pair of ears 22 which are struck up at each side of hinge 21 intermediate its ends. Hinge 21 is fashioned with a main body portion or leg 23 on which shield 12 is attached and a short foot portion 24 which extends beyond the pivotal connection provided by pin 20 in an angular direction with respect to the leg portion 23 of the hinge. As is best shown in Figures 3 and 4, foot 24 is offset angularly such that its free end 25 lies to the rear of pin 20 when the shield is disposed in the inoperative position and forwardly of pin 20 when the shield is pivoted to the operative position. The free end 25 of foot 24 is notched out as at 26 so as to permit engagement with the channel edges 17 of support 15 and

prevent the shield from being pulled downwardly away from visor 11. End 25 of foot 24 is arranged to abut against a stop 26 on support 15 to limit the pivotal movement of the shield in one direction to its depending operative position. In the inoperative position the shield contacts visor 11 which limits its movement in the upward direction. It will be observed that the angularly offset foot portion 24 of hinge 21 maintains spring 18 in a flexed condition at all times and the shield is thereby held in both its operative and inoperative position with spring tension.

When the shield is to be placed out of the way the wearer folds it upwardly to the position shown in Figure 3 where it lies underneath the visor. At this time the bearing end 25 of foot 24 is engaged within guides 17 to the rear of pivot pin 20. Spring 18 is flexed downwardly and thereby holds the shield in this position. In this inoperative position the shield is out of the way and the cap may be worn and used without any disturbance or obstruction from the shield. When the wearer desires to use the shield for protecting his eyes he merely flips the outer edge of the shield downwardly with his finger and the shield snaps to the operative position shown in Figure 4. During the initial stages of this movement, the end 25 of foot 24 moves forwardly in guides 17 and produces further downward flexing of spring 18. When end 25 passes forwardly beyond pivot pin 20, spring 18 begins to flex upwardly and serves to snap the shield downwardly to the operative position with the end 25 abutting against stop 26. It will be noted that at this time spring 18 is still flexed downwardly and the shield is retained in the operative position with spring tension.

What I claim is:

1. An eye shield attachment for a cap or the like of the type having a substantially horizontally extending visor at the front portion thereof for shading the wearer's eyes comprising a support member secured to the underside of the visor and having a guideway extending in a forward and rearward direction on the visor, a leaf spring means anchored at one end on said support, a shield, a hinge member, means forming a pivotal connection between said hinge member and the free end of said leaf spring, said hinge member having a leg portion and a foot portion inclined relative to each other, said shield being fixed to said leg portion for pivotal movement therewith to an inoperative position substantially underlying said visor and an operative position depending from the visor before the wearer's eyes in a plane substantially perpendicular to the line of vision, said foot portion having a toe at one end spaced from said pivotal connection and slidably in said guideway, the inclination of said foot portion relative to said leg portion being such that said toe moves along said guideway from a position rearwardly of said pivotal connection to a position forwardly of said pivotal connection when said shield is pivoted from the inoperative to the operative position, said foot portion maintaining said spring in a downwardly flexed position throughout the extent of movement of said shield.

2. An eye shield attachment for a cap or the like of the type having a substantially horizontally extending visor at the front portion thereof for shading the wearer's eyes comprising a support member fixed on the underside of the visor and having a guideway thereon extending fore and aft relative to the visor, a leaf spring

anchored at the front end of said support and extending rearwardly therefrom, a shield pivoted adjacent one edge to the rear end of said leaf spring, said shield being pivotable to an inoperative position substantially underlying the visor and an operative position depending from the visor before the wearer's eyes in a plane substantially perpendicular to the line of vision, a foot member pivotable with said shield and spacing the pivoted edge of said shield downwardly from said visor so as to flex said leaf spring downwardly at its rear end away from said support when the shield is disposed in either of said positions, said foot member having a toe portion slidably to and fro in said guideway when said shield is pivoted, said foot member being inclined to the plane of said shield such that said toe is shifted in said guideway to a position forwardly of the pivoted edge of said shield when the shield is pivoted to said operative position and over center to a position rearwardly of the pivoted edge of said shield when the shield is pivoted to said inoperative position, and a stop on said guideway for limiting the forward movement of said toe to the operative position of said shield, said toe in the operative and inoperative positions of the shield being inclined substantially to the plane of the visor.

3. The combination as set forth in claim 2 including means on said guideway engaging said toe to prevent separation of said toe from said guideway.

4. An eye shield attachment for a cap or the like having a visor, comprising a support mounted on the underside of the visor, an elongated spring mounted on the support so that it has a free part shiftable toward and away from the support by the flexing of the spring, a hinge member having a pivotal connection with the free part of the spring, said hinge member having a projecting portion normally yieldingly held against the support by the spring, a shield connected to the hinge member and angularly disposed relative to said projecting portion, the shield being pivotally shiftable, together with the hinge member, to and from an inoperative position in which the shield underlies the visor and an operative position in which the shield depends from the visor and is in front of the eyes of the wearer, the angularity of the shield and the said projecting portion of the hinge member relative to each other being such that the projecting portion of the hinge member shifts from one side to the other of a center line through the pivotal connection and perpendicular to the support, whereby the spring is caused to flex in said movements of the shield and yieldably holds the shield in both its inoperative and operative positions.
